PRESS LOADING DEVICE

Henry Sahlin, Detroit, and John R. Young, Farmington, Mich., assignors to General Motors Corporation, Detroit, Mich., a corporation of Delaware

Application October 1, 1940, Serial No. 359,272

8 Claims. (Cl. 271—8)

This invention relates to apparatus for feeding sheet metal blanks to presses. It might be used in its broader aspect for handling other work in connection with other machines, but it is primarily designed to be used for metal stamping presses.

In the drawings:

Fig. 1 is a side elevation of the apparatus connected with a metal stamping press.

Fig. 2 is an end elevation of the same.

Figs. 3 and 4 are sections on the corresponding section lines of Fig. 1.

Fig. 5 is an elevation similar to Fig. 1 but showing the table raised to slide the work in between the dies of a press.

The ram of the press is designated 1, the bed 2, the male die 3 and the female die 4. The female die is provided with a portion 5 which forms a knockout for releasing the work from the dies.

The feeding apparatus comprises a frame 6 which has side plates 7 and legs 8. This frame is provided with a cross rod 9 on the ends of which are sleeves 10 which form fulcrums or pivots for the side walls 11 of table 12. This table is provided with a plurality of rolls 13, nine on each side. The rolls are supported by the side walls 11 of the table. The frame is provided on one side with a dovetail trackway 14 in which a slide 15 travels. This slide 15 has two links 16 and 17 connected therewith and these links tie the dog 18 to the slide 15. Both ends of the dog are beveled.

The slide is connected by a link 19 with ram 1 of the press. This link is formed by two telescoping sections. The section 20 telescopes into the section 21 and a collar 22 is provided with a set screw 23 for adjusting the length of the link.

On the upstroke of the ram, dog 18 is carried upwardly with the slide by means of the shoulder 24. The beveled face 25 of the dog engages roller 26 on the table (see Fig. 4). This causes the table to be raised about the pivot. The table is in raised position in Fig. 5. In this position the blanks B slide down between the dies by gravity. They are properly positioned by suitable fingers (not shown) on the bed of the press or the lower die. When the ram rises as shown in Fig. 5, the roller 26 drops off the beveled face 25 of the dog and the flat face 27 engages the roller and this holds the table in the elevated inclined position shown in Fig. 5. The dog is still capable of further upward movement, as shown by the dotted line in Fig. 5.

When it reaches the upward limit the roll 26

drops across the lower beveled face 28. This allows the table to drop back to the horizontal position shown in Fig. 1. When the ram descends as shown in Fig. 1, the beveled lower face 28 of the latch strikes the roll 26 in its new downward position and this cams the dog to the collapsed position of the links shown in Fig. 1, where the links are turned up and the dog is substantially against the slide. In this position the dog can pass to the lower side of the roll, as is shown by comparing the full line showing of the dog in Fig. 1 with the dotted line showing of the dog. In the dotted line showing of the dog, the slide or actuator is now in position to again contact the roll 26 as the slide is lifted and to thereby raise the table.

This device is something like a ratchet in that it is a one way actuator, but it has an additional function inasmuch as before the full length of its stroke has been reached it allows the actuated member to be released and returned to its initial position by gravity. This actuator might be designated more specifically a parallel arm ratchet. This roughly describes its specific characteristics.

The blank is brought to the table by means of the conveyor belt 29 which causes it to move on to the rolls. The pivoted finger 30 prevents the blank from overrunning the rolls at the time the blank is first shoved onto the table by means of the conveyor. The finger or limit arm 30 is pivoted, as at 31, to the frame 7 of the apparatus. The left hand side of the finger or limit arm is connected with the pivoted table by pin and slot connection 32. Hence, when the table is lifted this pivot 31, slot and pin connection 32, serve to actuate the finger to drop it out of position as shown in Fig. 5, so that the work blank B is freely able to slide between the dies by gravity.

40 What we claim is:

1. In a blank or other work feeding apparatus for presses or other machines, the combination for a frame, a table pivoted thereon, normally resting in substantially horizontal position, and means arranged to cooperate with the machine into which the work blank is to be fed for tilting the table to an inclined position to allow the blank to slide off the table and into the machine where the operations are to be performed upon the blank, the said means comprising a draft device that picks up the table at one point and after a given tilting of the table releases and allows the table to drop.

2. In a blank or other work feeding apparatus for presses or other machines, the combination

of a frame, a table pivoted thereon, normally resting in substantially horizontal position, and means arranged to cooperate with the machine into which the work blank is to be fed for tilting the table to an inclined position to allow the blank to slide off the table and into the machine where the operations are to be performed upon the blank, said means arranged to be operated by the machine into which the work is to be fed, and said means comprising a draft device that engages the table when the machine is operated and raises one end of the same to a tilted position and then releases the table and allows the same to drop.

3. In a blank or other work feeding apparatus for presses or other machines, the combination of a frame, a table pivoted thereon, normally resting in substantially horizontal position, and means arranged to cooperate with the machine into which the work blank is to be fed for tilting the table to an inclined position to allow the blank to slide off the table and into the machine where the operations are to be performed upon the blank, said means arranged to be operated by a vertically traveling member on the machine into which the work is to be fed, and comprising a draft device provided with elements for engaging the table to tilt one end of the same as the vertically traveling member rises and then at a given point releases and allows the table to drop.

4. In a blank or other work feeding apparatus for presses or other machines, the combination of a frame, a table pivoted thereon and normally resting in substantially horizontal position, and means arranged to cooperate with the machine into which the work blank is to be fed for tilting the table to an inclined position to allow the blank to slide off the table and into the machine where the operations are to be performed upon the blank, said means arranged to be operated by a vertically traveling member on the machine into which the work is to be fed and comprising a link and slide with an actuating member for engaging a part on the table.

5. In a blank or other work feeding apparatus for presses or other machines, the combination of a frame, a table pivoted thereon and normally resting in substantially horizontal position, and means arranged to cooperate with the machine into which the work blank is to be fed for tilting the table to an inclined position to allow the blank to slide off the table and into the machine where the operations are to be performed upon the blank, means arranged to be operated by a vertically traveling member on the machine into which the work is to be fed comprising a link and slide with an actuating member for engaging a part on the table, said actuating member comprising a dog arranged to engage the part on the table and collapse and return to its initial position as the slide reaches the top of its stroke.

6. In a blank or other work feeding apparatus for presses or other machines, the combination of a frame, a table pivoted thereon, normally resting in substantially horizontal position, and means

arranged to cooperate with the machine into which the work blank is to be fed for tilting the table to an inclined position to allow the blank to slide off the table and into the machine where

5 the operations are to be performed upon the blank, said means arranged to be operated by a vertically traveling member on the machine into which the work is to be fed and comprising a link and slide with an actuating member for engaging 10 the part on the table, the said actuating member comprising a shoulder on the slide and a dog supported on this slide by a pair of parallel arms and having beveled ends which permit the dog to pick up the table in its upward movement by 15 engaging the part on the table in its upward movement and which release the table near the upper end of the stroke of the slide and then said dog returns inactively past the part on the table to its initial position.

20 7. In a blank or other work feeding apparatus for presses or other machines, the combination of a frame, a table pivoted thereon, normally resting in substantially horizontal position, and means arranged to cooperate with the machine

25 into which the work blank is to be fed for tilting the table to an inclined position to allow the blank to slide off the table and into the machine where the operations are to be performed upon the blank, means arranged to be operated by a

30 vertically traveling member on the machine into which the work is to be fed and comprising a link and slide with an actuating member for engaging the part on the table, the said actuating member comprising a shoulder on the slide and a

35 dog supported by a pair of parallel arms and having beveled ends which permit the dog to pick up the table in its upward movement by engaging the part on the table in its upward movement and which release the table near the upper end of the stroke of the slide and then said dog returns inactively past said part on the table to its initial position, the said part on the table comprising a roll that contacts with the beveled ends and also the intervening surface between the

40 45 beveled ends on the dog.

46 8. In a blank or other work feeding apparatus for presses or other machines, the combination of a frame, a table pivoted thereon, normally resting in substantially horizontal position, and means arranged to cooperate with the machine

50 into which the work blank is to be fed for tilting the table to an inclined position to allow the blank to slide off the table and into the machine

55 where the operations are to be performed upon the blank, said means arranged to be operated by the machine into which the work is to be fed, and a limit arm pivoted to said frame and also having a contacting connection with said tilted

60 table so that as the said table tilts with respect to the frame, the limit arm is swung out of the way to permit the work to slide down between the dies.
